Patented Dec. 13, 1927.

UNITED STATES PATENT OFFICE.

MAURICE R. LEAHY, OF KANSAS CITY, MISSOURI, ASSIGNOR OF ONE-HALF TO MICHAEL J. PHALEN, OF KANSAS CITY, KANSAS.

SIGN.

Application filed December 16, 1926. Serial No. 155,157.

This invention relates to improvements in signs and particularly to signs adapted to be used in connection with street lamps or lights for day and night indication of the 5 streets on which the lamps or lights are placed, and also for display lamps and signs of various kinds and for various purposes.

One object of this invention is the provision of a structure which may be readily 10 applied to lamps and lights of various characters and still carry information of all sorts.

A further object is the provision of a type 15 of device which will carry information for both the pedestrians on the sidewalks and the drivers of vehicles on the streets both at the corners and in the block between the corners.

A further object of this invention is the 20 provision of such a structure which is adapted to be used for many purposes and in which the names or other information are displaced by means of individual units containing letters, numbers or other characters 25 which are separate from each other and may be readily placed and removed from position for replacement or repair, and which are securely held in position, forming a device of this character having ready adaptability for 30 use in various locations. The individual units are provided with letters, numerals or other characters in such a form that they are visible in the daytime and also visible at night.

To the accomplishment of the foregoing and such other objects as may hereinafter appear, this invention consists in the construction, combination and arrangement of parts hereinafter described and then sought 40 to be defined in the appended claims, reference being had to the accompanying drawings forming a part hereof and which show, merely for the purpose of illustrative disclosure, a preferred embodiment of my invention, it being expressly understood, however, 45 that various changes may be made in practice within the scope of the claims without digressing from my inventive idea.

In the drawings—

50 Figure 1 represents an elevational view of one form of a lamp having the embodiment of my invention applied thereto.

Figure 2 is a side elevation of the construction embodying my invention on a 55 somewhat larger scale.

Figure 3 is a top plan view thereof, parts being shown in section to facilitate the disclosure.

Figure 4 is a vertical transverse cross section taken substantially on line 4—4 of Figure 3. 60

Figure 5 is a detailed inside perspective view of part of the construction to make a better disclosure of details.

Figure 6 is a perspective view of one of 65 the information containing units or elements.

Referring now to the drawings the numeral 1 designates a lamp or light which may be of various forms or conformations. In 70 itself it forms no part of this invention. It is circular in shape and, therefore, my sign device is circular in shape to fit the same.

This sign device includes an annular 75 member 2 having a bottom ring 3 and a top ring 4. The bottom ring 3 is provided with an upwardly extending flange 5 which forms an annular groove or recess 6 extending entirely around the member as a whole. 80 The top ring 4 is provided with a horizontally extending flat portion 7 and an upwardly extending annular flange 8 on the inner edge thereof. The lower or bottom ring 3 and the upper or top ring 4 and particularly the flat portion of the latter are connected by means of a plurality of bars or partitions 9. These bars or partitions are narrow in width and are arranged so as to provide considerable space therebetween, 85 these spaces being for the purpose of receiving letters or numbers or other characters making up the display. This construction has been described as being of separate parts but it is to be understood that it is 90 preferably formed of an integral structure, the material being stamped and cut out to provide the construction described. The outer side of the lower or bottom ring 3 is rounded or concave or convex as indicated 100 at 10 and the outer side of the upper or top ring 4 is likewise rounded as at 11.

The sign or display units or elements are 105 designated 12 and are in the form of rectangular pieces of glass having a black or other opaque background with the letters, numerals or other characters formed thereon by an opening in the opaque background and being covered by a thin coating 110 of paint of light color so as to be visible

in the daytime in light color and so as to be translucent so that the illumination of the lamp is visible therethrough at night-time.

Of course, this arrangement may be reversed so that the background is transparent and the numbers or letters opaque.

These units or elements 12 are arranged in the holder previously described, their lower portion and the edge fitting and resting within the groove 6. The units are arranged so as to give the desired information as to streets or other display entirely around the holder where necessary and the different designations may be separated by rosettes 13 at intervals. The rosette forms no part of this invention. The display of information desired if the lamp is at a street corner is made so as to carry one display for each sidewalk and one for each street, making four displays in all. The number of displays, of course, will depend upon the use to which the lamp is put and also its location.

These units or elements 12 having been mounted in position on the lower ring 3 and being supported thereby, are held in this position by means of clamping ring 14 which is located adjacent the upper annular member 4 and engages the upper portions of the units or elements 12. This clamping ring may be connected at one side to the holder by means of a screw or similar construction 15 and has a slidable, adjustable connection 16 provided by slotting its ends as at 17 to receive a nut and bolt connection 18. This will permit loosening for application and removal of the units and also tightening so as to clamp and securely hold them in proper position. This clamping ring may be made of any suitable material and instead of being adjustable as above described, may be a steel or other metallic snap ring.

Signs constructed to embody this invention are very inexpensive and durable and readily arranged and the display in them easily and quickly changed.

What I claim is:—

1. In combination in a device of the character described, a sign-holding member adapted to extend around and be supported by a lamp or lantern, said member having means for supporting a plurality of separate indicia-carrying elements and a flexible and adjustable member extending along said sign-holding member for holding said elements in position in said sign-holding member.

2. In combination in a device of the character described, a sign-holding member adapted to be applied to and supported by a lamp or lantern, said member having an annular support to receive individual indicia display elements and a flexible ring member connected to said sign-holding member and adjustable so as to bear against said elements

to hold them in position in said sign-holding member and permit their ready removal.

3. In combination in a device of the character described, a sign-holding member adapted to be applied to and supported by a lamp or lantern, said member having an annular support provided with a groove to receive individual indicia display elements, and a flexible ring member connected to said sign-holding member and adjustable so as to bear against said elements and hold them in position and permit their ready removal from said sign-holding member.

4. An attachment and sign display device for lamps comprising an annular band member adapted to be placed about said lamp having a body portion provided with a plurality of openings to permit the display of information therethrough, an annular base member, having an annular recess, a plurality of sign display units supported on said base member and positioned in said annular recess, a flexible holding member adjustably connected to said band and adapted to engage the upper portions of said sign display units to hold them in position, said sign display units being positioned so that the characters thereon are displayed through said openings in the band.

5. An attachment and sign display device for lamps comprising an annular band member adapted to be placed about said lamps having a body portion provided with a plurality of openings to permit the display of information therethrough, a top annular member extending inwardly from said body portion and a flange extending upwardly from the inner edge of said annular member, said band having a bottom portion provided with a flange extending upwardly from the inner edge thereof to form a recess to receive the sign display units, a holding member connected to said band and positioned adjacent said top member and provided with adjusting means whereby it may be moved to permit the insertion and removal of the sign display units.

6. An attachment and sign display device for lamps comprising an annular band member adapted to be placed about said lamps having a body portion provided with a plurality of openings to permit the display of information therethrough, a top annular member extending inwardly from said body portion and a flange extending upwardly from the inner edge of said annular top member, said band having a bottom portion provided with a flange extending upwardly from the inner edge thereof to form a recess to receive the sign display units, a holding member connected to said band and positioned adjacent said top member and provided with adjusting means whereby it may be moved to permit the insertion and removal of the sign display units, said holding

member being resilient and movable into close engagement with said sign display units.

7. An attachment and sign display device for lamps comprising an annular band member provided with a bottom annular member and a top annular member, said annular members being connected by means of a plurality of partitions formed of the material of the annular band member, said partitions being spaced apart to leave openings to permit the display of information therethrough, said bottom annular member being provided with a recess, a plurality of sign display units supported on said bottom annular member and positioned in said recess and having their upper ends engaging said top annular member and means for holding said display units in position in said annular band member with their upper ends in contact with the top annular member.

8. An attachment and sign display device for lamps comprising an annular band member provided with a bottom annular member and a top annular member, said annular members being connected by means of a plurality of partitions formed of the material of the annular band member, said partitions being spaced apart to leave openings to permit the display of information

therethrough, said bottom annular member being provided with a recess, a plurality of sign display units supported on said bottom annular member and positioned in said recess and having their upper ends engaging said top annular member and means for holding said display units in position in said annular band member with their upper ends in contact with the top annular member, said holding means comprising a flexible and adjustable band adapted to engage the display units near their top edges.

9. An attachment and sign display device for lamps comprising a one-piece metallic member in the form of an annular band cut out and shaped so as to provide a bottom annular member formed with a recess and a top annular member having an inwardly extending horizontal flange portion and spaced partitions connecting said top and bottom annular members, and a holding member connected to said annular band on the inside and adjacent the top annular part thereof, and adapted to cooperate with said horizontal flange to hold the display units in position therein.

In testimony that I claim the foregoing, I have hereunto set my hand this 7th day of December, 1926.

MAURICE R. LEAHY.
